UNITED STATES PATENT OFFICE.

LOUIS B. OLIN, OF CHICAGO, ILLINOIS.

REFRIGERATOR VEHICLE.

Application filed August 13, 1920. Serial No. 403,440.

To all whom it may concern:

Be it known that I, LOUIS B. OLIN, a citizen of the United States, and a resident of Chicago, in the county of Cook, State of Illinois, have invented certain new and useful Improvements in Refrigerator Vehicles, of which the following is a specification.

My invention relates to vehicles and particularly to an improved refrigerator truck 10 for distributing and delivering ice cream and the ingredients for cooling mixture such as ice and salt.

Among the important objects of my invention are: to provide a vehicle body having a refrigerator section so constructed and arranged that a large number of ice cream cans may be accommodated and conveniently located for handling to provide construction and arrangement whereby in a vehicle body 20 having refrigerator and also ice and salt storage sections, ice cream, whether in cans or in paper packages, or however packed, does not come in contact with the ice or salt, or the cooling mixture, nor do the ice cream 25 receptacles, or containers, come in contact with the ice or salt, or the cooling mixture; to provide improved construction and arrangement which will enable maintenance of the proper temperature of the cream with 30 little ice consumption; to provide construction and arrangement which will eliminate the necessity of frequent ice replenishment in the refrigerator to thereby effect saving in labor, ice and salt; to provide construction 35 and arrangement which will permit carrying of a large quantity of ice and salt to be furnished customers for use in their refrigerators in which the cream to be sold by them is stored; to provide construction 40 and arrangement whereby the ice and salt are readily accessible without requiring climbing back and forth on the vehicle; to provide construction and arrangement of insulating walls which will efficiently insulate 45 the refrigerator structure and the ice storing compartment so as to prevent ingress of heat and egress of cold; and in general to provide a delivery truck of the class described which will greatly facilitate the handling 50 of cream with a great saving in time and labor, and which will insure maintenance of the proper temperature of the cream with a minimum consumption of ice.

On the accompanying drawings, I show a 55 delivery truck in which the various features

of my invention are embodied. On these drawings

Fig. 1 is a side elevational view,

Fig. 2 is a plan view,

Fig. 3 is a sectional view on plane 3—3, 60 Fig. 1 and

Fig. 4 is a sectional view on plane 4—4, Fig. 2.

Referring to the drawings, the truck shown comprises the chassis frame 5 mounted on the wheels 6, the engine E, driver's seat and canopy 7 being at the front of the chassis. The space behind the driver's seat is taken up by my improved mechanism for storing cream and ice. The entire structure 65 is supported on cross beams 7' on the chassis frame 5 and the structure has two sections, namely the cream storing section 8 and the ice storing section 9. The sections have a common floor or bottom wall 10. The cream 70 storage section body part comprises outer and inner walls 11 and 12 separated by space for receiving temperature insulating material 13 such as cork. Preferably also, the outer and inner walls are lined on their 75 inner faces by sheet material 14 such as tar paper which assists in temperature insulation and is especially useful in preventing circulation of air. The cream section body part is open at the top, the edge 15 of the 80 opening flaring. To close the opening cover structures 16 and 17 are provided hinged at their sides and fitting together at their inner ends, suitable handles 18 being provided by means of which the covers may be 85 readily manipulated. The covers at their edges are beveled to fit the flaring mouth of the cream storing body structure.

Within the refrigerator body structure is the sheet metal container frame 19 whose 90 front is open and registers with the front wall of the body structure. This container frame at its other sides is spaced away from the body structure sides and also from the cover structure so as to leave surrounding 95 space for receiving the cooling medium such as ice and salt. As the body structure walls are of wood, the inner wall is preferably protected against the salt and moisture by a lining 20 of sheet metal. The container 100 19 is divided into an upper and a lower compartment by the partition or shelf 21. In the side wall of the refrigerator body structure are the openings 22, 23 and 24 for 105 which the door structures 25, 26 and 27 are 110

provided. The door structure 25 controls the access to the upper refrigerator compartment and the other doors control access to the lower compartment. In these compartments are stored the cans of ice cream to be distributed. The lower doors are readily accessible from the ground so that cans can readily be removed from or inserted into the lower compartment by a man standing on the ground. In order to make the upper compartment readily accessible, a step 28 is provided on which a man can stand when taking or returning cans in the upper compartment. The cover structure 15 and the various doors are constructed in the same manner as the body structure. They each have inner and outer walls lined with suitable sheeting and filled in between with temperature insulating material.

20 I have found that by sub-dividing the ice containing space, great efficiency results, the ice lasting a much longer time. I therefore provide vertical partitions 29 between the sides of the container 19 and the body structure to sub-divide the ice space into vertical pockets or compartments 30. These partitions terminate a sufficient distance above the bottom of the ice space to permit free circulation of water to the drain pipes 31 which extend downwardly. When the covers 16 and 17 are sprung open, ice can be readily charged into the compartments 30 together with the necessary quantity of salt and sufficient ice is charged in to cover 35 well the top of the container 19. The compartments prevent shifting and packing of the ice due to bumping and jolting of the vehicle during travel and the ice particles are thus held in more efficient position for 40 the generation of cold. I have found that with my improved sub-divided ice arrangement and the surrounding temperature insulating walls that it is necessary to replenish ice only twice a week in comparison 45 to replenishment morning and night necessary in prior construction.

The section 9 between the driver's seat and the refrigerator section is in the form of a rectangular tank for holding ice, and 50 taking up part of this tank is a receptacle 32 for salt, a supply of ice and salt being usually provided the customer for use in the refrigerator in which he stores the cream bought. Like the refrigerator structure, the ice tank has outer and inner walls 55 and 34 lined by suitable material 35 and filled between with cork or other temperature insulating material 36. The tank has the ice inlet opening 37 provided with the door structure 38 suitably hinged, and constructed to snugly fit the opening. Like the walls of the tank the door has double walls and is filled with temperature insulating material. At the side the tank has the 60 outlet opening 39 from which ice can be re-

moved into suitable pails by means of suitable instruments as for example, a shovel. A sliding door 40 slideable in a frame 40' is provided for controlling this opening. Instead of shoveling the ice, it can be caused 70 to flow from a tank into the receptacle by opening the door to the desired degree.

The salt receptacle is entirely within the ice tank and on the same side with the ice discharge door 40 the salt box has upper 75 and lower openings 41 and 42, these openings being provided with sliding doors 43 and 44 respectively. The upper opening is used for charging in salt and the lower opening is used for discharging salt. It is 80 evident that instead of having the various doors only at one side of the vehicle, a duplicate set of doors could be provided on the opposite side so that access could be had to the various compartments and ingredients from either side of the vehicle. The steps 28 and a similar steps 45 at the opposite side of the vehicle can run full length of the body so that ready access can be had to the various side doors and particularly 85 the top covers. At the rear end of the vehicle a frame 46 may be provided for receiving empty cream cans.

I thus provide an improved delivery vehicle which greatly facilitates the delivery 90 of cream and ice. The arrangement is such that very little climbing is necessary as nearly all the work can be done from the ground. The improved construction of refrigerator section involving the sub-divided ice space surrounded by temperature insulating walls effects considerable saving in labor and cooling material, it being necessary to replenish the ice supply 100 only after several days. The ice tank has a large capacity and the ice is protected against melting and wastage by the temperature insulating walls. The salt is also protected against moisture and wastage is 105 prevented. As the workman need not climb up on the vehicle, standing room for him can be eliminated and thus more space is available for storage purposes. In old constructions considerable floor space is required for the workman who is required 110 to climb on to the vehicle to get at the ice and the cream.

Having described my invention, I claim the following:

In a vehicle of the class described, the 120 combination of the running gear, a rectangular structure mounted thereon and divided into a refrigerator section and an ice and salt section, said structure having temperature insulating double walls, a container within the refrigerator section spaced away from the walls thereof, vertical partitions dividing said space into ice compartments, a side opening leading to said container, a door for said opening, an inlet 125

opening in the top of said structure for charging ice into the ice compartments and a cover for said opening, a collecting space for moisture below said ice compartments and a drain leading therefrom to the exterior of said structure, ice inlet and outlet openings for the ice section, a salt bin with-

in the ice section, and openings leading to said salt bin from the exterior of said structure. 10

In witness whereof, I hereunto subscribe my name this 9th day of August, A. D., 1920.

LOUIS B. OLIN.
